(57) CLAIM

The ornamental design for an eraser, as shown and described.

DESCRIPTION

FIG. 1 is a perspective top view of an eraser showing my new design;

FIG. 2 is a perspective bottom view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The stipple shading in the figures indicates a contrast in appearance.
